UNITED STATES PATENT OFFICE

2,102,014

APPAREL AND PARTS THEREOF

Jay H. Lind, Brooklyn, N. Y.

Application May 25, 1936, Serial No. 82,068

3 Claims. (Cl. 2—132)

This invention relates generally to linings and interlinings and more particularly to such material constructed primarily for preventing an article to which it is applied, as for example, a collar, cuff, collar-band, from curling, wrinkling, bulging or otherwise losing its shape and neat appearance obtained when freshly laundered. This invention further relates to the manufacture of new woven porous fabrics or materials possessing a high degree of flexibility combined with desired stiffness and imparting to a product to which it is applied qualities which render the same springy and capable of bending without either permanently creasing or breaking; and if the product is one which requires maintenance of shape, and a starched, neat and dressy appearance without the rigidity and discomfort incident to the use of starch, these attributes may be imparted to the product by embodying therein my invention. The qualities imparted make a product produced in accordance with my invention useful in various situations, and particularly as a lining or interlining for articles of wearing apparel, such as, collars, cuffs, shirts and parts thereof.

It is an object of this invention to provide a flexible sheet of, preferably woven, material embodying the aforementioned characteristics and imparting to an article the aforementioned qualities.

Referring to such garment elements, such as, collars, cuffs, neckbands, etc., heretofore many attempts have been made to attain the aforesaid object but usually at the expense of making the collar, etc. too bulky and difficult to launder, or of using a cementitious or cementitiously coated lining or interlining which although making the same waterproof, renders it non-porous thereby preventing free circulation of air through the article and free breathing of the skin in contact with the article required to keep the wearer cool and comfortable at all times. Further attempts have been made by providing a woven lining or interlining having horse-hair or mohair threads or strands, but results have not been satisfactory because of the characteristics of these materials.

It is a further object of this invention to provide portions of a garment, such as, for example, shirt collars, cuffs, neckbands, with a lining or interlining which may be of a light, net-like, woven or other porous construction and yet maintain its predetermined flexibility, style, shape and neatness under stress of wear and laundering without the use of stiffening mediums, such as, for example, starch or rubber, cellulosic or other cementitious compounds.

It is a further object of this invention to construct portions of garments, such as, collars, cuffs, neckbands, etc., with a metal cloth or a woven or knitted lining or interlining having wires, or metal or metallic threads or strands incorporated therein or otherwise integrally associated with the lining or interlining adding to the latter the desired stiffness without sacrifice of flexibility and still leaving the same of a light construction and permeability which will not interfere with free breathing of the skin against which the portion of the garment is worn; which as to such article may be washed and ironed, and starched if desired; and which may be worn as an unstarched article and as comfortable, being permeable to moisture, gases and vapors.

It is a further object of this invention to utilize such wires, metallic or metal threads or yarn in the interlining or lining fabric which will not corrode or rust or otherwise be affected by laundering or wearing.

The above several and other objects, purposes and advantages are attained by the novel design, construction and arrangement of parts, as hereinafter described and illustrated in the accompanying drawing, with respect to one embodiment of my invention when applied to a collar, and in which:

Fig. 1 illustrates a typical embodiment of the invention as applied to a collar stressing its neat appearance.

Fig. 2 is a view of a collar having incorporated therein a lining or interlining embodying the invention, the outer ply being broken away to show the interlining structure.

Fig. 3 is a view of a collar utilizing a lining or interlining embodying the invention in a modified form, the outer ply being broken away to show the interlining structure.

Fig. 4 is an enlarged diagrammatic detail of a portion of fabric embodying the invention, showing the wires or metal or metallic threads or yarns running in one direction only.

Fig. 5 is a view similar to that of Fig. 4, but showing the wires or metal or metallic threads running in two directions.

Fig. 6 is an enlarged diagrammatic view of a piece of material with braided metallic thread or yarn stitched thereto.

Fig. 7 is a fragmentary view of a lining or interlining incorporating the invention in a modified form.

By way of example, there is disclosed in Figs. 2 to 5, inclusive, a mixed woven fabric containing threads or yarns of textile material, such

as, for example, cotton or cotton mixture and metal or metallic threads or wires 12. The metal threads or wires 12 are spaced apart so as not to interfere with the sewing or stitching of the fabric to a ply or plies of material. I have found it practical to space the metal threads or wires about one-quarter to one inch apart. In this way they will not interfere with the sewing and the fabric will provide a very practical and efficient lining or interlining for an article of apparel, an example of which is shown in Figs. 2 and 3, in the form of a collar. If the metal threads or wires 12 are too closely woven it would make the lining or interlining too heavy. However, it is understood that the metal threads or wires 12 may be spaced apart any desired distance and that the woven fabric may be of any desired mesh. A collar or other article of wear embodying a lining or interlining of the above-mentioned character will not bulge, crease or curl, but will remain dressy and smooth, is permeable and will not interfere with the free breathing of the skin adjacent thereto.

The collars shown in Figs. 2 and 3 have an interlining made from fabric shown in Fig. 5, wherein wires or metal threads cross at right angles with other wires or metal threads. In the collar of Fig. 2 the wires or metal threads 12 run vertically and horizontally of the collar, whereas in Fig. 3, the wires or metal threads run on the bias, that is, diagonally of the collar. The interlining is sewed to the plies 13 of the collar in the conventional manner.

Fig. 4 shows the wires or metal threads 12 running parallelly and not crossing each other, the textile fabric threads or yarn 11 being interposed between the wires or metal threads 12.

A collar incorporating the features of this invention may be easily shaped and adjusted by the wearer.

In applying my new lining or interlining to, say, a collar, the same may be cut full, that is of equal dimensions to that of the outer plies, and thus be included in the seams, folded edges 45 and fold line (which is the line where the top or cape portion 16 folds over the neck band 17) of the collar. On account of the additional layer or layers of material around those sections of the collar, the wire ends will not protrude or cause 50 discomfort. However, if it is desired, the lining or interlining may be cut short to exclude the seams, folded edges or fold line when applied.

As shown in Fig. 7, the metal threads or wires 12' may be incorporated in or applied to the lining or interlining such that a margin or border 18 free of the metal threads or wires 12' is provided around the lining or interlining to fa-

cilitate the folding over of the edges of same in the construction of the collar. The folded-over or cape portion 19 and the neck band portion 20 of the interlining may be made in one piece, or in separate pieces and stitched together in constructing the collar.

The wire or metal threads selected for the purpose must be of the non-rust or non-corrosive type and capable of withstanding laundering, such as, for example, Monel metal, stainless steel, 10 nickel-chromium, etc. It is preferable to use cotton covered or other textile covered wire or metal thread.

The lining fabric shown in Figs. 4 and 5 may be termed a mixed woven fabric composed in part of fine, flexible non-corrosive wires or metal threads 12. In Fig. 6, there is disclosed a lining fabric which may comprise a textile fabric or composition 14 having stitched or otherwise attached thereto metal or metallic threads or yarn 20 15 to give the same non-wrinkling and non-curling qualities.

Although I have described my invention with respect to a collar, it is understood that the invention is applicable as a lining or interlining 25 for any form of wearing apparel or parts thereof wherein it is desirable to prevent curling, wrinkling and bulging of the article and to maintain the latter neat in appearance and dressy.

While I have here shown what I believe to be 30 simple and efficient forms of the invention it is to be understood that numerous alterations in the details of construction such as may be developed through the exigencies of use may be resorted to without transcending the scope of the 35 invention as defined by the appended claims.

Having described my invention what I claim as new and desire to secure by Letters Patent, is:

1. A shirt collar comprising an outer layer, an inner layer, and an intermediate layer, said intermediate layer comprising a woven fabric having substantially horizontal and vertical intersecting rust-resisting metallic threads, and non-metallic threads intermediate the metallic 45 threads.

2. A shirt collar comprising an outer layer, an inner layer, and an intermediate layer, the intermediate layer comprising a woven fabric having spaced apart intersecting corrosion-resisting 50 wires and textile threads between the wires.

3. A shirt collar comprising an outer layer, and a plurality of layers one of which is a woven fabric having spaced-apart intersecting corrosion-resisting wires and textile threads between 55 the wires.

JAY H. LIND.
